(57) **CLAIM**

I claim the ornamental design for a vent for legwear, as substantially shown and described.

DESCRIPTION

FIG. 1 is a front perspective view of a vent for legwear. FIG. 2 is a front elevational view of the vent shown in FIG. 1.

FIG. 3 is a rear elevational view of the vent shown in FIG. 1.

FIG. 4 is a right side elevational view of the vent shown in FIG. 1.

FIG. 5 is a left side elevational view of the vent shown in FIG. 1.

FIG. 6 is a bottomview of the vent shown in FIG. 1; and, FIG. 7 is a top view of the vent shown in FIG. 1.

1 Claim, 7 Drawing Sheets
